CAST METAL APPLIQUÉ FILIGREE

Benjamin Kipnis, Brooklyn, N. Y.

Application July 12, 1949, Serial No. 3,843

Term of patent 7 years

(Cl. D54—2)

To all whom it may concern:

Be it known that I, Benjamin Kipnis, a citizen of the United States, and residing in the county of Kings, city and State of New York, have invented a new, original, and ornamental Design for a Cast Metal Appliqué Filigree, of which the following is a specification, reference being had to the accompanying drawings, forming part hereof and in which the single figure is a plan view of the cast metal appliqué filigree, showing my new design.

I claim:

The ornamental design for a cast metal appliqué filigree, substantially as shown.

BENJAMIN KIPNIS.
